UNITED STATES PATENT OFFICE.

FREDERICK E. KOHLER, OF CANTON, OHIO, ASSIGNOR OF ONE-HALF TO
ISAAC HARTER, OF SAME PLACE.

POST-HOLE DIGGER.

SPECIFICATION forming part of Letters Patent No. 327,557, dated October 6, 1885.

Application filed April 4, 1885. Serial No. 161,221. (No model.)

To all whom it may concern:

Be it known that I, FREDERICK E. KOHLER, a citizen of the United States, residing at Canton, in the county of Stark and State of Ohio, have invented certain new and useful Improvements in Post-Hole Diggers, of which the following is a specification, reference being had therein to the accompanying drawings.

10 This invention relates to improvements in the implements used in digging post-holes, for transplanting, &c., it pertaining more especially to those of the class illustrated in patent, No. 68,903, to M. L. Roberts, September 15 17, 1867.

Figure 1 is a side view of an implement embodying my invention. Fig. 2 is a section on line $x\ x$, Fig. 1. Fig. 3 is a face view of one of the shovels detached from the other. 20 Fig. 4 is a perspective of one of the ring-segments with its socket detached from the other parts. Fig. 5 is a face view of the digger. Fig. 6 is a view showing a modification of the hinge devices. Fig. 7 is a section showing the manner of attaching the shovels.

I employ a supporting-ring at the top made in segments $A\ A'$, the ends of one segment being fitted to the other, preferably lying inside, and being pivoted together by means of 30 a bolt or rod passing through the overlapping end. These parts of the implement may be made as strong as necessary and of any size suitable for the work to which they are to be put.

35 B B represent the blades or scoops, which are secured at their ends to the ring-segments $A\ A'$, these scoops being either of the form shown or of any other which may be preferred.

40 When diggers of this class have been made in the manner shown in the aforesaid patent, the lower ends of the handles have not been situated in the way which I find most advantageous, and in order to permit the handles to 45 be arranged in a superior manner I expand the ring-sections $A\ A'$ inwardly at about the midway point of each, the expansions being shown at $a\ a$. With these are formed or to them are secured socket-pieces $C\ C'$, which extend upward, each having an inner wall, c , and side walls, c' . The handles D are, at their

lower ends, fastened in the sockets, respectively, by means of bolts, as at d . The sockets and expanded parts of the rings which carry them are arranged directly opposite to each other in relation to the hinge—that is to say, so that they move directly toward and from each other when the parts are opened or closed upon the hinge. Therefore the handles move in the same plane, and the strain exerted when in operation is distributed uniformly. They can throughout their entire length be brought comparatively closely together, so that both can be grasped by one or both hands, and yet at the same time they avoid the great inconvenience and danger incident to those constructions in which the handles have been so arranged relatively to the hinge as to pass each other more or less, the danger being that the hands of the operator may be caught 65 between them. The handles in diggers of this latter class are generally parti-circular in section, and flat upon one side, coming together with a scissors movement.

With my digger the handles, when brought 70 to their innermost positions, can either be still grasped separately by the hands of the operator, or both can be firmly clamped together by his hands.

The two parts of the digger are joined together 75 by means of a hinge engaging with the ring-segments $A\ A'$. The ends a' of segments A' are so shaped as to overlap the ends a^2 of segment A , and said ends are provided with apertures, through which pass one or more pivots or hinge-pieces, G, one being shown in Fig. 2, and two in Fig. 6.

In order to prevent the handles being forced 80 too closely together at the lower ends, offsets are formed on the parts $C\ C'$, they being shown at F and F'. Preferably, the part F is recessed, as at f, to receive the tongue f' on the part F'.

When the handles are brought together, these parts f' and F act as braces to prevent any lateral movement or swinging, and therefore 95 the pivoting parts are relieved of strain.

A digger of the character which I have shown and described can be manufactured much more quickly and cheaply than can those heretofore produced, having the same efficiency so far as 100 they are known to me.

What I claim is—

1. In a digger, the combination of the ring-
segment A, provided with an inward expansion
and socket-piece, and the ring-segment
A', provided with a corresponding inward
expansion and sockets C', said sockets lying in
5 the same transverse plane, and the hinge se-
cured to said ring-segments independently of
the sockets, as described.

2. The combination of a ring-segment, A,
10 having the inward expansion, the socket C,
provided with an offset, F, the ring-segment
A', having an inward expansion, and the socks-
ets C, provided with an offset, F', the ring-
sections being pivoted together, substantially
15 as set forth.

3. The combination of the ring-segments A
A', hinged directly together and adapted to
carry the shovels, each being provided with a
handle-receiver situated on a vertical line in-

side of the lines of the shovels and arranged 20
transversely opposite to each other across the
hinge-line, whereby the handles are, when
closed, comparatively close together without
being in contact or passing each other, sub-
stantially as set forth. 25

4. In a digger, a connecting device between
the handle and shovel consisting of a ring-seg-
ment, A, provided with a hinge-holder or
pivot-holder at the end and with an inward
expansion, as at a, between the ends carrying 30
an upward-projecting handle-socket.

In testimony whereof I affix my signature in
presence of two witnesses.

FREDERICK E. KOHLER.
